UNITED STATES PATENT OFFICE.

ROBERT E. POINDEXTER, OF INDIANAPOLIS, INDIANA.

SAW GAGE AND JOINTER.

SPECIFICATION forming part of Letters Patent No. 417,277, dated December 17, 1889.

Application filed September 2, 1889. Serial No. 322,720. (No model.)

To all whom it may concern:

Be it known that I, ROBERT E. POINDEXTER, a citizen of the United States, residing at Indianapolis, in the county of Marion and State 5 of Indiana, have invented certain new and useful Improvements in a Combined Saw Gage and Jointer, of which the following is a specification.

My said invention consists in certain improvements in that class of tools used in fitting saws for use, and relates more especially to the means by which the jointing-file is held in place on the frame, and to the form of the gage for the clearing or raking teeth, as will 15 hereinafter be more particularly described and claimed.

Referring to the accompanying drawings, which are made a part hereof and on which similar letters of reference indicate similar 20 parts, Figure 1 is a perspective view of a tool embodying my said invention; Fig. 2, a front elevation; Fig. 3, a top or plan view; Fig. 4, a horizontal sectional view looking downwardly from the dotted line 4 4 in Fig. 2; Fig. 5, a transverse vertical sectional view looking toward the right from the dotted line 5 5 in Fig. 2, and Fig. 6 a detail view 25 partially in section.

In said drawings the portions marked A 30 represent the main frame of the device; B, the locking device by which the file is held in position; C, the gage for the clearing or raking teeth, and D the file.

The frame A is a casting of the form shown, 35 and is provided with projections and flanges, against which the file is clamped when the tool is in position for use. The relation of the file to the remainder of the device when the tool is used for jointing the ends of the 40 points of the teeth is indicated by dotted lines in Fig. 1, and its position when used for jointing the sides of the points of the teeth is indicated by the dotted lines in Fig. 2.

As will be noticed by an examination of the 45 drawings, the file is held in either position by the same clamping device B, one edge of which is adapted to come in contact with said file when in one position and the other edge when the file is in the other position. Said clamping device B is mounted on a boss or projection a on the frame A, and is held there by a head or nut or equivalent device a'. The

slot in said device B which passes over this projection a is inclined somewhat, so that when said clamping device is moved in one 55 direction it will force one edge against the file when it is on that side of it, and moved in the other direction the other edge will be forced against the file when located upon that side, as shown by the drawings, Figs. 1 60 and 2. The boss or projection a has wings or flat surfaces, as shown in Fig. 6, which keep its edges in parallel relation to the planes occupied by the file when in position at all times. As will be noticed by an examination 65 of Fig. 5, the file, when in the position to joint the sides of the points of the teeth, is slightly below the surface of the flanges on the tool, thus allowing for the set in said teeth.

The gage C for the clearing or raking teeth 70 is formed of hardened metal and secured to the frame A by a screw A', which passes through said frame and the boss a thereon, and on its point carries the head or nut a', which holds the clamping device B in position. The hole in this gage through which this screw passes may be, and preferably is, 75 slightly larger than the body of the screw, in order that a slight adjustment may be effected; but such an adjustment at the most is only 80 trifling, and is not commonly necessary at all, and therefore a slight looseness in the hole for the screw is all that is required.

The particular novelty in my gage consists 85 in a projection c extending out from the center of its upper portion, the top surface of which is parallel with the top surface of the gage. This projection extends between the two prongs of the clearing-tooth when the device is in position for use for the purpose of 90 jointing such teeth, and extends to the other side of the saw from the device, and thus insures that the operator shall keep his file substantially parallel, and obviates all danger of jointing off the points of these clearing-teeth 95 on a downward slant, as might be, and often is, the case where my improved device is not employed. Where it is employed, tipping up the end of the file next the operator raises it entirely free from the points of the teeth. 100

Having thus fully described my said invention, what I claim as new, and desire to secure by Letters Patent, is—

1. The combination, in a saw-tool, of the

- frame having flanges or projections against which a file may rest, and a clamp portion adapted to move longitudinally of said frame on a projection or boss thereon, said clamp portion having an inclined slot which passes over said boss or projection, whereby when it is moved its edges are caused to approach or recede from the file when said file is in place.
2. The combination, in a saw-tool, of the frame A, having a boss or projection *a* and flanges or projections against which a file may rest, and a clamp portion B, having an inclined slot and mounted upon said boss or projection, substantially as described, and for the purposes specified.

3. In a saw-tool, in combination with the frame thereof, a gage for the raking or clearing teeth, having a projection in the same plane as its operative surface adapted to pass between the prongs of said clearing-teeth ²⁰ when the tool is being used for jointing said clearing-teeth, substantially as set forth.

In witness whereof I have hereunto set my hand and seal, at Indianapolis, Indiana, this 6th day of August, A. D. 1889.

ROBERT E. POINDEXTER. [L. S.]
